ATTORNEY

UNITED STATES PATENT OFFICE

ROY E. PITCHER, OF HENRYETTA, OKLAHOMA

ROLLING SCREEN

Application filed February 7, 1928. Serial No. 252,578.

The present invention relates to screens and particularly to screens which are attached to the window sashes and are adapted to be extended or retracted as the sashes are raised or lowered as the case may be.

An object of the invention is to improve and simplify the construction of screens of this character.

A further object is to provide such a screen which will cover the entire space open by raising or lowering the window either from the top or bottom as the case may be and which will be movable in slots in the sides of the window frame and through a slot at the top or bottom of the window frame according to the mounting of the screen and which will be provided with means preventing the dislodgment of the screen from the slots.

Other objects are to provide novel and effective means for bracing the window frame adjacent the slots formed therein.

Still further objects and advantages will appear from the subjoined specification and will be included in the claim appended thereto.

In the drawings:—

Figure 1 is a longitudinal section vertically through a window and window frame constructed in accordance with this invention.

Figure 2 is a cross section in a horizontal plane.

Figure 3 is a detail fragmentary view of a portion of the screen showing the rubber buttons attached to the side thereof.

Figure 4 is a fragmentary view on an enlarged scale illustrating the details of the rubber buttons.

Figure 5 is an enlarged detail view showing the connection of the screen to one of the window sashes.

Figure 6 is a detail view of the rubber strip to be attached to one of the window sashes in order to complete the closure by the window and screens.

Figure 7 is a detail view of one of the braces for connecting the portions of the window frame at the sides of the slots formed therein.

Referring to the drawings in detail, 10 50 designates the window frame, 11 and 12 are

sashes slidable in the frame in the usual manner, 13 and 14 designate screens which are mounted on rollers 15 and 16 respectively located in housings 17 and 18 at the top and bottom of the window frame, the rollers being 35 of the usual window shade type and adapted to be actuated by a spring contained therein, the construction of said rollers being no part of the present invention. Further details being omitted a mere representation thereof 40 is all that is shown.

The window frame is provided in the body 50 as illustrated with slots 19 and 20 arranged through the transverse portions of the frame at the top and bottom thereof, said 55 slots being of sufficient width to accommodate and permit the passage of the screens therethrough. The free ends of the screens are attached respectively to the upper and lower sashes 12 and 11 by means of strips of metal 70 indicated at 21 and 22 on the drawing. The portions of the sashes to which the screens are attached are provided with inset portions at 23 and 24 respectively of sufficient depth to receive the screen and the plate, the outer 75 surfaces of said plates being flush with the surfaces of the portion of the frame to which they are attached.

The sides of the window frames are likewise provided with slots forming combinations of the slots 19 and 20 and extending downwardly and upwardly as the case may be from said end slots a distance sufficient to take care of the entire travel of the screens in the downward and upward movement of 85 the respective window sashes. These slots are designated by the numerals 25 and 26. The edges of the screens project through these slots on both sides of the window and are prevented from dislodgment therefrom by 90 means of rubber buttons 27 formed in two parts 28 and 29 one of which is provided with a screw threaded stem 30 and the other with a threaded aperture 31 adapted to receive said threaded stem for connecting the sections of 95 the buttons thereto, the buttons constituting when assembled substantially a sphere and are connected with the screen by inserting the stem through the mesh thereof and threading the section 29 thereon.

The slots formed in the sides of the frame are connected preferably by U-shaped brace members 32 which are adapted to span the slots and to be connected by screws or other suitable means 33 to the portions of the window frame on either side of the slots, the arched portion of the brace being adapted to extend around the projecting side edges of the screen. The lower horizontal portion of the upper window sash is preferably indicated at 34 and is provided with a rubber strip 35 secured thereto by rubber contacts and projecting beyond the edge thereof to bear against the window pane of the window. The rubber strip is preferably tapered or wedge-shaped in configuration, the taper being toward the window pane with which it contacts as shown in Figure 2.

In this manner the opening of the window is completely closed at all times. The upper portions of the lower window sashes and the lower portions of the upper window sashes may be beveled in order to make a tighter fit when the respective sashes are lowered and raised, as shown at 36 and 37. The projecting portions of the screen at the sides of the window frame are protected by housings 37 as shown in Figure 3 of the drawings.

The operation of the device is briefly as follows: When the upper sash is lowered, the upper screen 13 will be drawn out of the casing 17 unwinding as it is drawn downwardly from the roller 15 and the reverse will take place when the connected window sash is raised. A similar operation will take place when the lower sash is raised and lowered with respect to the screens 26, the sides of the screens riding in the slots 25 and 26 and being prevented from dislodgment therefrom by the rubber buttons 27. The member 35 effects a closure in all positions of the windows and prevents the flies from passing between the sashes into the interior of the room.

Having described my invention what I claim is:

Guiding means for the side edges of the rolling type of window screen, comprising a window frame having slots in its sides for receiving the edges of the screen and U-shaped brackets connected with the outer faces of the side parts of the frame and bridging the slots.

In testimony whereof I affix my signature.
ROY E. PITCHER.
